Primary Examiner — Carla J Wright(74) *Attorney, Agent, or Firm* — Bridgeway IP Law Group, PLLC; Jihun Kim; Hyun Woo Shin(57) **CLAIM**

The ornamental design for a case for electronic communications device as shown and described.

DESCRIPTION

FIG. 1 is a front, right-side, and top perspective view of a case for electronic communications device showing my new design;

FIG. 2 is a rear, left-side, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a rear, left-side, and top perspective view thereof showing the case for electronic communications device in an alternate configuration and in an environment of use.

The dash-dash broken lines in the drawing figures and the regions bounded by broken lines form no part of the claimed design. The dash-dash broken lines depict environmental subject matter and portions of the case for electronic communications device that form no part of the claimed design. The dot-dash broken lines depict boundaries of the claim and form no part thereof.
